(57) **CLAIM**

We claim the ornamental design for a merchandise display rack, as shown and described.

DESCRIPTION

FIG. 1 is a front perspective view of a merchandise display rack according to an embodiment of the present invention; FIG. 2 is a back perspective isometric view thereof; FIG. 3 is a front elevational view thereof;

FIG. 4 is a back elevational view thereof;

FIG. 5 is a left elevational view thereof;

FIG. 6 is a right elevational view thereof;

FIG. 7 is top plan view thereof;

FIG. 8 is a front perspective view of a merchandise display rack according to an embodiment of the present invention; FIG. 9 is a back perspective isometric view thereof;

FIG. 10 is a front elevational view thereof;

FIG. 11 is a back elevational view thereof;

FIG. 12 is a left elevational view thereof;

FIG. 13 is a right elevational view thereof;

FIG. 14 is top plan view thereof;

FIG. 15 is a front perspective view of a merchandise display rack according to an embodiment of the present invention; FIG. 16 is a back perspective isometric view thereof;

FIG. 17 is a front elevational view thereof;

FIG. 18 is a back elevational view thereof;

FIG. 19 is a left elevational view thereof;

FIG. 20 is a right elevational view thereof;

FIG. 21 is top plan view thereof;

FIG. 22 is a front perspective view of a merchandise display rack according to an embodiment of the present invention; FIG. 23 is a back perspective isometric view thereof;

FIG. 24 is a front elevational view thereof;

FIG. 25 is a back elevational view thereof;

FIG. 26 is a left elevational view thereof;

FIG. 27 is a right elevational view thereof; and,

FIG. 28 is top plan view thereof.

The broken lines are for illustrative purposes only and form no part of the claimed design.
